(57) **CLAIM**

The ornamental design for a body fluid cartridge device, substantially as shown and described.

DESCRIPTION

FIG. 1 is a perspective view of a body fluid cartridge device. FIG. 2 is a right side view of the body fluid cartridge device of FIG. 1.

FIG. 3 is a left side view of the body fluid cartridge device of FIG. 1.

FIG. 4 is a front view of the body fluid cartridge device of FIG. 1.

FIG. 5 is a rear view of the body fluid cartridge device of FIG. 1.

FIG. 6 is a top view of the body fluid cartridge device of FIG. 1; and,

FIG. 7 is a bottom view of the body fluid cartridge device of FIG. 1.

The broken lines immediately adjacent the shaded areas represent the bounds of the claim, and all other broken lines are directed to environment. The broken lines form no part of the claimed design.

1 Claim, 5 Drawing Sheets
